UNITED STATES PATENT OFFICE.

LEWIS FREDERICK WEBER, OF FRANKFORT-ON-THE-MAIN, GERMANY, ASSIGNOR TO
UNITED SHOE MACHINERY COMPANY, OF PATERSON, NEW JERSEY, A CORPORA-
TION OF NEW JERSEY.

MACHINE FOR TREATING SHOES WITH LIQUIDS.

1,149,235.

Specification of Letters Patent. Patented Aug. 10, 1915.

Application filed November 29, 1912. Serial No. 734,068.

To all whom it may concern:

Be it known that I, Lewis F. Weber, a citizen of the United States, residing at Frankfort-on-the-Main, in the Kingdom of Prussia, Germany, have invented certain Improvements in Machines for Treating Shoes with Liquids, of which the following description, in connection with the accompanying drawings, is a specification, like reference characters on the drawings indicating like parts in the several figures.

This invention relates to machines for treating boots or shoes with liquids and is herein disclosed as embodied in a machine for cleaning the uppers of shoes. The machines of this character commonly used in shoe factories usually comprise a rotary brush, pad or other tool (hereinafter for convenience referred to as a brush) and some means for supplying the brush with a cleansing fluid, such for instance as water. In order to secure the best results, it is essential that the brush be supplied with a certain quantity only of water, too little being insufficient to clean the shoe properly or requiring an undue length of time to perform the cleaning operation, and too much being objectionable in that it spatters from the brush over the adjacent parts of the machine. The machines of this character at present on the market, however, have, so far as I am aware, no provision by which the quantity of cleansing fluid can be regulated to suit the requirements of the work.

It is therefore an important object of this invention to devise a machine having means for controlling the delivery of cleansing fluid to the brush. Preferably this control is effected through the presentation of the work to the brush. In the preferred construction the arrangement is such that while the delivery of fluid to the brush takes place only when the brush is operating on the work, provision also is made for determining automatically the maximum rate of delivery of fluid to the brush and for enabling the workman to vary the rate of delivery through the action of the work on the brush.

The invention will be clearly understood from the following description of one embodiment thereof when read in connection with the accompanying drawings, in which,—

Figure 1 is a view in side elevation of an

upper cleaning machine constructed in accordance with this invention, certain parts of the machine being cut away in order to show more clearly the details of construction; and Fig. 2 is a cross-sectional view on the line 2—2, Fig. 1.

The machine shown in the drawings comprises a rotary brush 1 mounted on a shaft 2, which is supported for rotation in any suitable manner, and mechanism for delivering water or other liquid to the brush. This mechanism consists of a tank 3, a roll 4 rotatably mounted in said tank and a second roll 5 mounted to rotate in peripheral contact both with the roll 4 and also with the brush 1. The drag of the bristles on the roll 5 causes it to rotate and to drive the roll 4. The latter roll thus delivers water to the roll 5 which in turn carries it to the bristles of the brush. It will be evident that the rate of delivery of water to the brush will depend upon the rate of rotation of the roll 5 and in order to control this rate of rotation the roll is provided with a centrifugal brake. This brake consists of a hub fast on the spindle of the roll 5 and two weighted arms 6 and 7, each pivoted to the hub and having attached thereto springs 8 and 9 respectively which tend to turn the arms inwardly about their pivots. This mechanism revolves inside a stationary casing 10, having a peripheral flange which overlies the weighted arms 6 and 7. The flange may, if desired, be lined with leather or other similar material as indicated at 11. When the roll 5 is rotated rapidly the weights 6 and 7 are urged outwardly by centrifugal inertia, against the tension of the springs 8 and 9 until, when the roll attains a certain speed, the weights come in contact with the lining 11 of the stationary casing 10 and the friction created in this manner exerts a retarding action on the roll, preventing any further increase in its speed and, consequently, limiting the rate of delivery of liquid to the brush.

The tank 3 together with the rolls is mounted for adjustment toward and from the periphery of the brush, the adjusting means comprising a cap plate 12 on which the tank sits and an adjusting screw 13 which supports the cap plate and is threaded through a part of the machine frame. A guideway 14 formed in the wall of the ma-

chine frame at each side receives a projection from the tank 3 and controls the path of the adjusting movement of the liquid supplying mechanism. The tank also may be provided with a water gage 15 of the usual construction to indicate at any time the level of the water in the tank.

Positioned in front of the liquid supplying mechanism and at the lower side of the brush is a stripper plate 16 which extends entirely across the periphery of the brush and is supported in a holder 17 having a cylindrical shank 18 mounted in a vertical slideway formed in the walls of a basin 19 which constitutes part of the machine frame. The lower end of the holder 17 is supported on an adjusting screw 20 by means of which the position of the stripper plate can be adjusted. Any turning movement of the stripper plate is prevented by a set screw 21 threaded through the walls of the basin 19 and entering a vertical groove in the shank 18 of the holder. The water that is scraped off the brush by the stripper plate 16 flows into the basin 19 and is conducted away by a pipe 22 opening into the bottom of this basin. The brush is partly inclosed by a hood consisting of a lower stationary section 23 and an upper section 24 pivoted to the lower section at 25.

In operating the machine the liquid supplying mechanism is adjusted so that the roll 5 will be engaged firmly by the bristles of the brush and the stripper plate 16 is set with its upper edge projecting slightly into the body of the brush. When the machine is running idly, that is, when the brush is not operating on the work, the stripper plate will bend the bristles backwardly out of their normal positions. An appreciable length of time is required for the bristles to straighten out again; and due to the rotation of the brush the ends of the bristles will travel during their straightening action in a line substantially like that indicated by the line A, Fig. 1. This path, of course, will vary with the speed of rotation and the length and resiliency of the bristles of the brush. It will thus be evident from an inspection of Fig. 1 that when the machine is running idly the effect of the stripper plate is to deflect the bristles in such manner that they entirely skip the conveying roll 5. Consequently the action of the conveyer is interrupted at this time and the delivery of liquid to the brush is stopped. When, however, the work is pressed against the brush it then deflects the bristles so that in returning to their normal positions they follow a path substantially as indicated for example by the line B, Fig. 1, thus entirely skipping the stripper plate 16, but straightening out again in time to contact with the roll 5 and drive it in the usual manner. This arrangement not only results in caus-

ing the delivery of water to the brush to take place only when the brush is operating upon the work but also enables the workman to vary the rate of delivery of liquid while the work is being treated; for while the maximum rate of rotation of the roll 5 and consequently the maximum rate of delivery of liquid to the brush is determined by the centrifugal brake, still the rate of rotation of the conveyer roll will be less if the brush engages the roll merely with the tips of its bristles than if a greater portion of the bristles contacts with the roll. The workman, therefore, can vary the driving engagement between the brush and the roll by pressing the work against the roll so hard that the bristles will only straighten out in time to have their tips contact with the roll or by holding the work against the brush with a lighter pressure, thus enabling the bristles to resume their normal positions more quickly and to engage the roll more firmly. This control of the rate of delivery of water to the brush is thus effected by changing, temporarily, the shape of the brush.

While the machine herein disclosed embodies three features through which the supply of liquid to the brush is controlled, it will be evident that it is within the spirit of this invention to use any one of these features independently of the others. It will be evident also that the invention is not limited in its application to the particular type of machine disclosed.

Having described my invention, what I claim as new and desire to secure by Letters Patent of the United States is:—

1. In a machine of the class described, the combination of a driven brush arranged for operative engagement with work presented at one portion of its path of movement, and means for supplying liquid to the brush by engagement with the brush at another portion of its path of movement, the position of said liquid supplying means being so related to that portion of the path of movement of the brush at which the work is presented that the rate of delivery of liquid to the brush will be varied by changes in the shape of the brush caused by engagement with the work.

2. In a machine of the class described, the combination of a driven brush, means for supplying liquid to said brush, and means for acting on the brush when the work is out of contact therewith to interrupt the delivery of liquid to the brush by said means.

3. In a machine of the class described, the combination of a rotary brush, means for engaging said brush and supplying liquid thereto, and means for deflecting the bristles of the brush out of contact with said supplying means when the brush is not operating on the work.

4. In a machine of the class described, the combination of a rotary brush, means operated by the brush for supplying liquid thereto, and means for acting on the brush to interrupt its operative connection with said supplying means when the work is out of contact with the brush. 65
5. In a machine of the class described, the combination of a rotary brush, means for engaging said brush and delivering liquid thereto, and a stripper plate located in front of said liquid delivering means in position to deflect the bristles of the brush out of contact with said means, said stripper plate being located behind the position at which the work is presented to the brush so that the pressure of the work against the brush will deflect the bristles out of contact with the stripper plate. 70
- 10 6. In a machine of the class described, the combination of a driven brush arranged for operative engagement with work presented at one portion of its path of movement, and liquid supplying means for the brush arranged to be operated by engagement with the brush at another portion of its path of movement, the position of said liquid supplying means being so related to that portion of the path of movement of the brush at which the work is presented that the operation of said means is controlled by the deflection of the bristles of the brush through engagement with the work. 75
- 15 7. In a machine of the class described, the combination of a rotary brush, means for engaging said brush and supplying liquid thereto, and means for acting on said brush to deflect the bristles to cause them to skip said supplying means, said deflecting means being adjustable toward and from the periphery of said brush. 80
- 20 8. In a machine of the class described, the combination of a rotary brush, means for supplying liquid to said brush comprising a rotary conveyer, a stripper plate located in front of said liquid supplying means in position to deflect the bristles of the brush out of contact with said supplying means, means for adjusting said stripper plate toward or from the periphery of the brush, and means for adjusting said conveyer toward or from said brush. 85
- 25 9. In a machine of the class described, the combination of a rotary brush, means operated by the brush for supplying liquid to said brush, and automatic means for controlling the rate of delivery of liquid to the brush by said supplying means. 90
- 30 10. In a machine of the class described, the combination of a rotary brush, means for supplying liquid to said brush comprising a rotary conveyer, and means operated by the motion of said conveyer to limit the rate of delivery of liquid to the brush by said supplying means. 95
- 35 11. In a machine of the class described, the combination of a rotary brush, means for supplying liquid to said brush comprising a rotary conveyer, and a brake constructed and arranged to control automatically the rate of rotation of said conveyer. 100
- 40 12. In a machine of the class described, the combination of a rotary brush, means for supplying liquid to said brush, a stripper plate positioned with its edge in engagement with the periphery of the brush, a holder supporting said plate, means for adjusting said holder and stripper plate toward or from the periphery of said brush, and a basin located adjacent to said stripper plate in position to catch the liquid scraped off said brush by said plate. 105
- 45 13. In a machine of the class described, the combination of a rotary brush, a tank, a rotary conveying roll supported in said tank and arranged to be engaged by the periphery of said brush and to be rotated thereby, and means operated by the motion of said conveyer for limiting the rate of delivery of liquid to the brush. 110
- 50 14. In a machine of the class described, the combination of a driven brush arranged for operative engagement with work presented at one portion of its path of movement, and means for supplying liquid to the brush comprising a liquid conveying roll arranged to be rotated by contact with the brush, the position of said roll being so related to that portion of the path of movement of the brush at which the work is presented that the extent of operative engagement of the bristles of the brush with the roll will be varied by deflection of the bristles through contact with the work. 115
- 55 15. In a machine of the class described, the combination of a driven brush arranged for operative engagement with work presented at one portion of its path of movement, means for supplying liquid to the brush, and a stripper plate for removing surplus liquid from the brush, said plate being so positioned relatively to that portion of the path of movement of the brush at which the work is presented that the bristles of the brush deflected by contact with the work will not engage said plate. 120
